SEPARABLE AND COLLAPSIBLE ARTICLE
SIMULATING A CHRISTMAS TREE

Marie Fridinger, Vienna, Austria

Application June 12, 1948, Serial No. 32,688
In Austria October 10, 1947

2 Claims. (Cl. 41—15)

1

This invention relates to an article made of paper, cardboard or similar foldable sheet material, which can be constructed to be used as a container for display and other purposes, decorative device, Christmas tree, plaything, etc.

It is an object of my invention to provide an article of the character referred to which consists, and is easily formed, of a number of parts and can be disassembled just as easily.

An important object of this invention is to provide an article, the parts of which can be packed and shipped by the manufacturer, and sold in stores, in flat or collapsed condition, the parts being constructed so as to be readily set up by the user.

Another object of my invention is to provide an article which can be erected by setting up and assembling its individual parts without the need for gluing, stapling or the like and without employment of elastic bands, cords or similar fastening means.

Another object of my present invention is to provide an article, the parts of which, upon being set up and assembled, represent a structure strong enough for the intended purpose.

A further object of the invention is to provide an article which is neat in appearance, inexpensive to manufacture and purchase, and well suited for the purposes for which it is intended.

Still another object of my invention is to provide an article, the parts of which, upon disassembly, can be individually collapsed into flat condition.

To the accomplishment of the foregoing and the other objects which will hereinafter appear, my invention consists in the elements of a collapsible article and the relation of these elements one to the other, as are more particularly described in the following specification and sought to be defined in the claims. The specification is accompanied by drawings in which:

Fig. 1 is an elevation of an article embodying features of my present invention;

Fig. 2 is a plan view of a part of the article of Fig. 1;

Fig. 3 is a perspective view of a basketlike article according to this invention;

Fig. 4 is an elevation of a part of the article of Fig. 3, with part of the structure shown in section;

Fig. 5 is a plan view of the part of Fig. 4;

Fig. 6 is similar to Fig. 5, but showing the part in flat condition.

Fig. 7 is a fragmentary detail of a part of the article of Fig. 3 and is explanatory of the formation of that part;

2

Fig. 7a is an enlarged plan view of the article of Fig. 3, with a part omitted;

Fig. 8 is a perspective view of a modified article;

Fig. 9 is an elevation of still another modification simulating a Christmas tree;

Fig. 10 is an enlarged plan view of one of the branched structures of the Christmas tree;

Fig. 11 is a section taken on the line 11—11 of Fig. 10;

Fig. 12 is an elevational view of a modified branched structure;

Fig. 13 is an enlarged elevation of a part of the Christmas tree; and

Fig. 14 illustrates a further modification of the article of my invention.

Referring to the drawings in greater detail, particularly Figs. 1 and 2, the article generally designated 10 comprises a carrier or post 12 and a bowl-like member 14. The post has the form of a six-sided pyramid and is formed from an integral blank which is scored so as to furnish the six sides of the pyramid. The blank may be of cardboard and its longitudinal edges may be sealed together to form the pyramid. Instead of being adhesively united, the edges may also be stapled together. The post has no base and is hollow. The bowl 14 is made from an integral circular blank, for instance, of cardboard provided with a hexagonal center hole 16, the original shape of the bowl blank and hole 16 being indicated by dash-dotted lines in Fig. 2. The hole 16 is shaped to fit over the post 12 approximately at the desired height.

The bowl blank has radial scores and is folded in alternate direction so as to give the bowl a zigzag pattern. The folds along the scores u_1 , u_2 , and u_3 make the flanking sectors turn upwardly, whereas the folds along the scores d_1 , d_2 (not visible in Fig. 1) and d_3 turn the flanking sectors downwardly. From Fig. 1 it will be seen, for instance, that the sectors s_1 and s_2 , which flank the score u_1 , are bent upwardly, whereas s_2 and s_3 are bent downwardly with respect to the score d_1 .

Generally speaking, my invention uses a post in upright position and a member of bowl-like shape which is held by the post, as can be seen from Fig. 1, in a substantially horizontal position. Said member is provided with a hole of such shape that simply by passing the upper end of the post through the hole the member is placed on, and held by, the post. In the embodiment of Figs. 1 and 2, the hole 16 is congruous with a horizontal section through the post 12.

In accordance with my invention, I make use of flat integral blanks to form both the post and

bowl. In order to form a member of bowllike shape, as shown in Fig. 1, I bend the blank so as to impart a hollow form to the blank. As explained above, I provide radial scores and flex the panels or sectors between the scores in alternate succession. Instead of a circular bowl blank, a blank of any other shape may also be used.

It will be understood that the post 12 can easily be collapsed by flattening same in one of the diagonal planes. The bowl 14 can be flattened by pressing it into the plane of its blank.

Referring now to Figs. 3 to 7a, the article generally designated 18 comprises a post 20, a bowl-like member 22 and a loop 24. The post 20 is a four-sided pyramid which again is formed from an integral blank by scoring and folding and by uniting the longitudinal blank edges. The loop 24 is a doubled blank and is permanently fastened to the vertex of the pyramid as by gluing, but the loop may instead be simply put into an opening at the vertex of the pyramid. The bowl 22 is formed from a circular blank 22' (see Fig. 7), which is scored along the lines 23 and has a centrally located quadrilateral aperture 26', a serrated circumference 28' and a small sectorlike cutout 30, by sealing the radial edges 32 and 34 together, for instance, in an overlapping fashion. The edges 32 and 34 assume the positions shown in Fig. 7a, and the flat bowl blank 22' turns into a frusto-pyramidal bowl 22 with a serrated periphery 28 and an aperture 26 which conforms in shape to the horizontal section through the pyramid 20 at the height where the bowl is to be held.

From Figs. 7 and 7a, it will be seen that the central portion of the bowl blank which coincides with the cutout 26' or 26 is incised along the lines 35 to form four flaps 36. These flaps may be bent upwardly along the score lines 38 to lie against the sides of the post, when the bowl is put in place, and to give the bowl a safe seat and rigidity to the whole structure (see Fig. 3). Such flaps may be bent downwardly as well to serve the same purpose.

The post 20 can similarly be flattened as the post 12. In Figs. 5 and 6, the post 20 is shown in erect and flat condition, respectively. The bowl 22 can be folded upon itself along the dash-dotted fold lines 40, indicated in Fig. 7a to be brought into flat condition.

In Fig. 8, a three-tiered article is shown well suited to be used as a centerpiece. The post 42 is a six-sided pyramid and the three frusto-pyramidal bowls 44, 46 and 48 are formed from blanks with hexagonal apertures to spacedly fit over the post. They are arranged on the post so that the smallest is on top and the largest at the bottom. The six flaps 50 of each of the bowls are formed, as explained with respect to Figs. 7 and 7a, and are shown directed downwardly. It will be clear that the points of the flaps of the bottom bowl, when necessary, may be folded around the base of the pyramid inwardly of the pyramid. For decorative purposes, a tassel 51, which may be formed of differently colored slips of paper, is put into an opening at the vertex of the pyramid.

Referring to Figs. 9 to 13, in this embodiment, which simulates a Christmas tree, the stemlike post 52 supports seven branched structures 54. The post is a cone made from a suitably shaped blank by uniting the two longitudinal edges. The branched structures are made from blanks of starlike form, each provided with a center hole 55 (see particularly Fig. 10). Essential to 70

my invention is the starlike shape of the horizontal members used in this embodiment. Each branch or point 56 of each branched structure is folded along its longitudinal center line 58, the folded halves being directed downwardly. The provision of the branches 56 and, consequently, notches 57 formed between the branches makes it possible to obtain a rooflike structure of a zigzag pattern by folding the branches of one and the same blank in the same sense, in the present case, downwardly. The rooflike form can best be seen from Fig. 11, and the zigzag pattern from Figs. 9 and 12.

From Fig. 9, it will be seen that the branched structures are arranged so that the largest structure is at the bottom and the next smaller structure follows one upon the other until the smallest is on top. The branched structures are provided with holes 55 conforming to the respective sections through the conical post 52. The branched structures may be placed on the post so that the branches of each structure overlie the notches of the structure immediately underneath. An arrangement, as shown in Fig. 9, whereby the branch of each structure overlies a notch underneath simulates a richly branched tree.

In Fig. 12, a branched structure 54' is shown which simulates branches of a Christmas tree equipped with small candles 60. These candles are obtained by providing three-sided cuts 62 in the branches 56' and by bending the cut-out material upwardly. The branches 56' are folded along 58' as are the branches 56 along 58.

Preferably, I use for the cone 52 and the branched structures 54 and 54' green paper, either alone or with cardboard as a back layer, the latter material being used to obtain a stronger construction. To obtain a variegated effect, I paste differently colored particles of paper 64 onto the branches 56 or 56'.

The Christmas tree is crowned, as can be seen from Fig. 13, with a star 66 made, for instance, of paper of silver or gold color. Passed through a hole 68 in the star and spread over the tree are silver- or gold-colored threads 70 to increase the decorative effect. An electric bulb may be put into the inside of the cone 52 to make light radiate through a few incisions provided in the cone.

Each of the branched structures 56 and 56' simulates five branches. It is obvious that the number of branches may vary. It will also be understood that by varying the shape of the branches different foliage and different kinds of trees may be represented.

The embodiment of Fig. 14 uses two posts 72 together with a single oval-shaped bowl 74, the latter being formed from a flat integral blank provided with two cutouts by adhesively uniting the edges 76 and 78 which define each of the cutouts.

It should be understood that more than two posts can also be used with a single horizontal member and that two or more horizontal members can be used with two or more posts as well as with one post. It is, of course, also possible to support a horizontal member by a number of posts, say, three, and to support another horizontal member merely by one or two of those three posts.

It is believed that the construction and handling of the elements or parts of separable and collapsible articles for practicing my invention, and the many advantages thereof, will be understood from the foregoing detailed description thereof. It will be clear that the parts may be

constructed and combined in innumerable ways to produce an infinity of articles, all of the parts being originally simple blanks, easy to set up and to assemble, the articles being easy to separate. The separate parts can be folded or pressed into flat condition, both before assembly and after disassembly. The article of my invention can be made to be used for various purposes. To use it as a toy, various blanks are provided with directions how to make and set up the parts and in which different ways to assemble such parts.

It is obvious that frusto-conical and frusto-pyramidal posts may be used instead of cones and pyramids, respectively. Essential to my invention is the tapering form, the gradual diminution toward the upper end making it possible that the horizontal parts, each being provided with a hole, are simply put over the posts to be held in place.

The holes in the horizontal parts may be arranged in any way, for instance, along a center line. If more than one post is used, the holes in one horizontal part are usually of identical shape, unless posts of different size are used.

It will be apparent that while I have shown and described my invention in preferred forms, the many indicated changes and modifications may be made without departing from the spirit of the invention defined in the following claims.

I claim:

1. In an article simulating a Christmas tree, comprising a trunklike post narrowed toward the upper end, and branched structures, the branched structures being of starlike shape and gradually changing diametrical dimensions, the post supporting the branched structures in an axially spaced relationship, the largest branched structure being at the bottom, and each next smaller branched structure being over the next

larger one, each branched structure being provided with a center hole, the center hole of each branched structure corresponding to a different section through said post, each larger branched structure being provided with a larger hole, the branches of each branched structure being creased along their center lines, the portions alongside the creases being turned downwardly, the post and branched structures being made of blanks of foldable sheet material, the post being formed by fastening together the radial edges of the substantially sector-like post blank, the post and branched structures being assembled by slipping the largest branched structure first over the post and each next smaller branched structure next, the post and branched structures, upon disassembly of the article, being adapted to be flattened.

2. In the article according to claim 1, the branched structures being provided with three-sided cuts, the portions thus partly dissociated being bent away to stick up.

MARIE FRIDINGER.
